UNITED STATES PATENT OFFICE.

ALEXANDER DICKINSON, OF SEATTLE, WASHINGTON.

DESIGN FOR A BADGE.

No. 39,985.

Specification for Design.

Patented May 18, 1909.

Application filed January 18, 1909. Serial No. 473,029. Term of patent 3½ years.

To all whom it may concern:

Be it known that I, ALEXANDER DICKINSON, a citizen of the United States, residing at Seattle, in the county of King and State of Washington, have invented a new, original, and ornamental Design for Badges, of which the following is a specification, reference being had to the accompanying drawing, forming part thereof.

The figure is a plan view of a badge, showing my new design.

I claim:

The ornamental design for a badge, as shown.

ALEXANDER DICKINSON.
